UNITED STATES PATENT OFFICE.

ARTHUR J. FORWARD, OF OTTAWA, ONTARIO, CANADA.

INDEX-CLIP.

1,347,942.

Specification of Letters Patent. Patented July 27, 1920.

Application filed September 22, 1917. Serial No. 192,758.

To all whom it may concern:

Be it known that I, ARTHUR JAMES FORWARD, a subject of the King of Great Britain, residing at Ottawa, in the Province of Ontario and Dominion of Canada, have invented certain new and useful Improvements in Index Clips, of which the following is a specification.

The present invention relates to clips depending for their action on the resilient contact of the members thereof with opposite sides of the material to be held.

It is the object of this invention to provide a clip of the character referred to of simple construction, which not only performs the function of ordinary clips, but also acts as an indicator for purposes of display, reference or classification.

It is the more particular object of this invention to provide a device so constructed and arranged that the indicator projects beyond the edge of the material held by the clip and contiguous thereto and in substantially the same plane therewith.

For a fuller understanding of the invention reference is had to the appended drawings in which—

Figure 1 is a perspective view of one form of the invention;

Fig. 2 is a plan view showing its application;

Fig. 3 is a perspective view of a modification;

Fig. 4 is a plan view of another modification;

Fig. 5 is a plan view of another form.

Although the clip may be formed in various ways, as for instance by stamping out a suitable blank from sheet material and subsequently bending it to the desired shape, I preferably form it by bending a single piece of wire or strip of metal or other suitable material.

All forms comprise a lower portion, which is the clip proper, and an upper portion which is the receptacle for a display element, as exemplified by Fig. 2.

In all forms a definite length of wire is preferably bent to form two symmetrical halves having the point midway between the ends as the starting point and working simultaneously toward the ends or vice versa, as may be found most expeditious.

In Fig. 1, a loop 1 of substantially triangular shape is formed as one part of the clip proper. Continuing the operation of

bending, the wire or strip is bent outwardly to form arms 2 and 3, then downwardly, rearwardly and upwardly to form loops 4 and 5 and arms 6 and 7, then forwardly, 60 downwardly and inwardly to form the loops 8 and 9 and the arms 10 and 11, then upwardly, rearwardly and downwardly to form the loops 12 and 13 and the arms 14 and 15 which terminate adjacent the free 65 edge 17 of the triangular loop 1. The arms 2, 6, 10 and 14 on the one side and 3, 7, 11 and 15 on the other side connected by loops 4, 8 and 12 and 5, 9 and 13 respectively form the receptacle for a card 16 or 70 strip of paper, metal, celluloid or other material (Fig. 2) on which may be written, stamped or printed words, letters, signs, figures or symbols for display.

The receptacle or holder is so arranged 75 relatively to the clip as to project beyond the edge of the material held thereby and occupy a conspicuous position for the purpose specified without taking up undue space or interfering materially with the 80 disposition of the material tagged.

In the use of the clip the arms 14 and 15 are bent to lie normally below the clamping member or loop 1 (as shown in Fig. 1) leaving the space between the loops or folds 85 of the holder clear for insertion of the card or strip. When the card is in place, the arms 14 and 15 are moved transversely outwardly and then upwardly whereby they are brought above the clamping member or 90 loop 1 and by their own resiliency on being released assume substantially the position above the clamping member shown in Fig. 2. The arms 14 and 15 may be suitably 95 bent or curved downwardly so that when they are brought above the clamping member 1, they are in resilient contact with it at the points of intersection and the material is firmly held between loop 1 and the arms 14 and 15 by the inwardly exerted 100 pressure of the clamping members.

The arms 14 and 15 perform the further function of holding securely the card or strip 16 in the card holder due to the fact that when they are brought above the loop 105 1 they press firmly against the lower edge of the card and thereby force the card upwardly against the upper folds or loops 8, 9 and 12, 13 and also against the arms 2 and 3. The pressure thus exerted increases with 110 the thickness of the card and of the material held in the clamping members.

The form in which the wire or strip is bent and the size of the clip may be varied considerably for the purposes specified.

The modification shown in Fig. 3 is similar to the form shown in Fig. 1. The clamping member 20, however, has the form of a ring.

The ends of the arms 14 and 15 may be left straight or may have the tips thereof 10 bent into circular, triangular, rectangular or other convenient forms in such manner as to protect the paper or other material to be held by the clip against mutilation.

Such bends of the arms 14 and 15 at the 15 tips thereof, instead of being completely closed, may form loops or hooks 21 (Fig. 4) such that upon the ends of the arms being brought together, they will, by interlocking with each other, provide a means for temporarily holding the free ends of the arms 20 together so as to form one continuous clamping member similar to loop 1.

One alternative form of the invention is shown in Fig. 5 where the arms 25 and 26 25 are shorter than the clamping member 27 and instead of being carried outside the member 1 in Fig. 1 are moved transversely inwardly and then upwardly above clamping member 27 and by their own resiliency 30 assume a position above and rest on the inwardly projecting portions 28 and 29 of the clamping member 27 and are in resilient downward contact therewith at the points of intersection and in upward resilient contact with the lower edge of the card to be inserted in the holder 30. The portions of the wire forming the card holder are bent inwardly from the points 31 and 32 to form arms 33 and 34, then bent to form loops 35 35 and 36 and the arms 37 and 38, then bent to form loops 39 and 40, arms 41 and 42, loops 43 and 44 and the free arms 25 and 40 26. The various loops and arms just described produce a holder for cards similar 45 in all respects to that shown in Figs. 1 and 2.

While I have herein shown and described what I consider preferred forms of the invention, it is obvious that there is considerable latitude in the mechanical construction for carrying it into practice without sacrificing any of the advantages thereof.

I claim:—

1. A clip having a card embracing portion and a sheet clamping portion so related as to hold the card and sheet in abut-

ting relation in substantially the same plane, the clip being formed of a single piece of wire, one member of said clamping portion consisting of a loop whose end portions are curved to form card embracing portions, the free ends of such end portions extending downwardly to form a clamping member adapted to coöperate with the loop-clamping member, said free ends being 60 adapted to be brought over the loop clamping member.

2. A clip having a card embracing portion and a sheet clamping portion so related as to hold the card and sheet in abutting relation in substantially the same plane, the clip being formed of a single piece of wire, one member of said clamping portion consisting of a loop whose end portions are curved to form card embracing portions, 70 the free ends of such end portions extending downwardly to form a clamping member adapted to coöperate with the loop-clamping member, said free ends being 75 adapted to be brought over the clamping member and having hooks formed thereon.

3. A clip having a card embracing portion and a sheet clamping portion so related as to hold the card and sheet in abutting relation in substantially the same plane, the clip being formed of a single piece of wire, one member of said clamping portion consisting of a loop whose end portions extend laterally, longitudinally and transversely 80 and are curved to form card embracing portions, the free ends of such end portions extending downwardly to form a clamping member adapted to coöperate with the loop clamping member, said free ends being 85 adapted to be brought over the loop clamping member. 90

4. A clip having a card embracing portion and a sheet clamping portion so related as to hold the card and sheet in abutting relation in substantially the same plane, the clip being formed of a single piece of wire, 100 one member of said clamping portion consisting of a loop whose end portions extend laterally, longitudinally and transversely and are curved to form card embracing portions, the free ends of such end portions extending downwardly to form a clamping member adapted to coöperate with the loop clamping member, said free ends being 105 adapted to be brought over the loop clamping member and having hooks formed thereon. 110

In testimony whereof I affix my signature:

ARTHUR J. FORWARD.
